No. 6, & 11.

Dec. 12, 1871

UNITED STATES PATENT OFFICE.

GEORGE D. DUDLEY, OF LOWELL, MASSACHUSETTS, ASSIGNOR TO EDWARD P. WOODS, DANIEL SHERWOOD, AND CYRUS H. LATHAM, OF SAME PLACE.

DESIGN FOR A THREE-BOTTLE CASTER.

Specification forming part of Design No. 5,411, dated December 12, 1871.

To all whom it may concern:

Be it known that I, GEORGE D. DUDLEY, of Lowell, in the county of Middlesex and State of Massachusetts, have invented a Design for a Three-Bottle Caster or stand, of which the following is a specification:

The nature of my design is fully represented in the accompanying photographic illustration, to which reference is made.

The caster is composed of a handle, legs, bottle-rings, and the frame to which they are secured. The handle is formed of one or more wires, plain or twisted, ornamented with a coil of twisted wire, and bent into the shape shown to form the bow of the handle, and then united to the upper parts of the twisted strands which diverge from the curved part of the handle and extend downward to each side of the horizontal

frame supporting the bottle-rings. These strands, two upon each side of the frame, are bent for a short distance after they meet the frame horizontally or parallel with it, and secured thereto by the clasps or metal bands that hold the outer rings to the frame; and the end of each strand is then bent down into the curved form shown in the illustration, to form the legs for the stand. As thus formed, my design may be used as a caster or as a stand for toilet perfumery and other bottles.

I claim—

The design for a caster or stand, substantially as shown in the accompanying photographic illustrations.

Witnesses:

GEO. D. DUDLEY.
ABEL WHITNEY,
I. A. WHITNEY.
